200,418

FOOTBALL DART GAME BOARD

Roger C. Olson, 297 Reservoir Road, Newington, Conn.

Filed Feb. 24, 1964, Ser. No. 78,739

Term of patent 14 years

(Cl. D34—5)

FIG. 1 is a plan view of a football dart game board showing my new design:

FIG. 2 is an edge view thereof.

The dominant features of my design reside in the portions shown in full lines.

ons show

I claim:
The ornamental design for a football dart game board,
as shown and described.

References Cited by the Examiner

UNITED STATES PATENTS

D. 92.785 7/34 Veazey ----- D34—8

OTHER REFERENCES

Parker Games, 1958, page 24, lower left, Pigskin.

EDWIN H. HUNTER, Primary Examiner.